(57) **CLAIM**

The ornamental design for a bottle, as shown and described.

DESCRIPTION

FIG. 1 is a top plan view of a bottle according to my new design.

FIG. 2 is a front elevational view thereof.

FIG. 3 is a right side elevational view thereof.

FIG. 4 is a left side elevational view thereof.

FIG. 5 is a rear elevational view thereof.

FIG. 6 is a bottom plan view thereof.

FIG. 7 is a top, front, and left side, perspective view thereof; and,

FIG. 8 is a top, right side, and rear, perspective view thereof. The broken lines in the figures form no part of the claimed design.
